DESIGN FOR A NECKTIE RACK

Sidney Owen and Erwin Goeller, Lincoln, Nebr.;
said Goeller assignor to said Owen

Application October 19, 1939, Serial No. 87,734

Term of patent 7 years

To all whom it may concern:

Be it known that we, Sidney Owen, a citizen of the United States, and Erwin Goeller, a national of Germany who has declared his intention of becoming a citizen of the United States, both residing at Lincoln, in the county of Lancaster and State of Nebraska, have invented a new, original, and ornamental Design for a Necktie Rack, of which the following is a specification, reference being had to the accompanying drawing, forming part hereof.

In the drawing:

Fig. 1 is a side elevational view of a necktie rack embodying our new design.

Fig. 2 is a perspective view of the necktie rack in opened or extended condition, as seen from the side opposite to that shown in Fig. 1.

The characteristic features of the present design are shown in full lines in the drawing.

We claim:

The ornamental design for a necktie rack, substantially as shown and described.

SIDNEY OWEN.
ERWIN GOELLER.
